UNITED STATES PATENT OFFICE.

ROSWELL A. LANCEY AND CHARLES W. SMITH, OF TOWNSEND, MASSACHUSETTS, ASSIGNORS TO ANSON D. FESSENDEN, OF TOWNSEND, MASSACHUSETTS.

BARREL-FINISHING MACHINE.

SPECIFICATION forming part of Letters Patent No. 755,374, dated March 22, 1904.

Application filed April 1, 1903. Serial No. 150,592. (No model.)

To all whom it may concern:

Be it known that we, ROSWELL A. LANCEY and CHARLES W. SMITH, of Townsend, county of Middlesex, and Commonwealth of Massachusetts, have invented certain new and useful Improvements in Barrel-Finishing Machines, of which the following is a specification.

Our invention relates to machines for finishing the ends of barrels, and has for one of its objects to finish both ends of a barrel at one operation.

Another object of our invention is to provide a mechanism that will finish barrels to a uniform length and diameter and leave the surface smooth.

Still another object of our invention is to provide means for finishing the ends of barrels of different lengths and diameters.

A further object is to provide means for automatically centering, finishing both ends of a barrel at one operation, and for releasing and ejecting the barrel from the machine when finished.

The mechanism for accomplishing these objects is set out in the drawings and description forming a part of this specification.

In the drawings, Figure 1 is a side elevation of the machine, showing all its operating parts in inoperative position and a barrel in dotted lines in position upon the guides ready to be clamped and operated upon. Fig. 2 is a plan view of our improved barrel-finishing machine. Fig. 3 is a longitudinal sectional elevation through line 3 3, Fig. 2. Fig. 4 is a sectional elevation on line 4 4, Fig. 2. Fig. 5 is an isometric sectional view on line 5 5, Fig. 4. Fig. 6 is a sectional view on line 6 6, Fig. 4, looking to the right. Fig. 7 is a sectional view on line 7 7, Fig. 6. Fig. 8 is a sectional view of one cutter-slide and one of the adjusting devices on line 8 8, Fig. 4.

Similar letters refer to similar parts throughout the several views illustrating our invention.

In the drawings, A represents the bed upon which the various parts of our mechanism are

mounted. A' A' represent legs supporting the bed.

B B represent movable head-stocks, in 5° which are revolvably mounted the shafts B², which support the cutter-carrying heads B³ B³. Mounted upon the shafts B² B² are the driving-pulleys B' B'.

b b are platens which are slidably mounted 55 upon ways on the top of the bed A in such manner that they are free to move longitudinally on said bed. Upon these platens b b the head-stocks B B are adjustably secured by means of the adjusting-bolts b¹¹ b¹¹ b¹¹ b¹¹, 60 so that they may be adjusted longitudinally, as desired, by the adjusting-screws b¹² b¹².

There are attached to the platens b b the connecting-levers b' b', which levers are connected at their lower ends to the reciprocating bars b² b² by means of the links b⁹ b⁹. Said levers b' are pivoted upon rocker-shafts b⁶ b⁶, which are mounted in bearings in the bed A. Said levers b' b' have the upwardly-extending portions b⁷, which are pivoted to the connecting-links b⁸, which links are pivoted, by means of pins b¹⁰, to the movable beds b. The two reciprocating bars b² b² are caused to move longitudinally by means of rolls b³ b³, pivoted upon them, and the revolving cams b⁴ b⁴, which 75 contact with said rolls b³ b³. The cams b⁴ b⁴ are mounted upon the revolving shaft b⁵. Said shaft b⁵ is revolved by means of the gears d d' d² d³, mounted upon their respective shafts d⁴ and d⁵, the shaft d⁵ being revolved 80 through the medium of the pulley d⁶. The shafts d⁴ and d⁵ are mounted in suitable bearings attached to the bed A.

It will be seen by an inspection of Fig. 1 that the shaft b⁵ has two cams b⁴ b⁴ identical 85 in outline mounted upon it, each driving one of the reciprocating bars b² b², which, being identical in outline, construction, and operation, only one will be described. These reciprocating bars b² are mounted in suitable bearings c c, attached to the bed A of the machine.

The mechanism described, comprising the reciprocating bars b² b² and the levers b' b' and their respective driving mechanism and con-

nections, operate to move the head-stocks B B toward and from each other upon the bed A of the machine to enable them to perform the operation of moving upon each end of the 5 barrel and of clamping it firmly in an adjusted position, so that the cutter-heads may operate to finish its ends.

The cams b^4 b^5 are so shaped that the head-stocks B B will have a period of rest when 10 they are in their extreme outward positions in order that the finished barrel may be ejected and another placed in position to be finished. Another period of rest occurs when the head-stocks B B are in their extreme inward 15 positions, this to give the cutters time to finish the ends of the barrel while it is held by the clamping-rings B⁴ B⁵.

As before stated, the revolving heads B³ B³ are mounted upon the revolving shafts B² B² 20 and carry the cutter-heads and cutters which finish the ends of a barrel. The revolving heads B³ have guides n n n n across their faces at right angles to each other, as is seen in Fig. 4, the guides consisting of dovetail grooves, 25 in two of which is mounted the slide o, which extends nearly across the revolving head B³ and has mounted at one of its ends the leveling-cutter e and at its other end the chamfering-cutter f. This slide o is moved longitudinally 30 by means of the diagonal cam-grooves j j in the inner faces of the lugs k, in which the pins j" bear and freely slide, as is more clearly illustrated in Fig. 7.

The means for operating the movable slide 35 o is as follows: The said slide o is moved by means of a pin in the inner end of the shaft l, operating in diagonal cam-groove j in the cam-block k when said shaft l is moved longitudinally by means of the lever l', which may be 40 attached to said shaft l by any means that will permit it to revolve freely but to be immovable longitudinally in the end of said lever l'. The lever l' is attached to the rocker-shaft l'', which in turn is reciprocated by means of 45 the lever l'', the link l'', the lever l'', which latter is moved longitudinally by means of a roll secured to its end, which operates in the groove l'' in the slide-block l''. The slide-block l'' is moved vertically by means of the cam m, 50 which contacts with the roll l'', mounted on said slide-block l''. The cam m is what might be termed a "track-cam"—i. e., it operates both to move the block l'' up and to pull it down, thereby through the connections here- 55 in set forth operating to move the cutters into cutting position to finish the ends of a barrel and to pull them back out of contact with the barrel end when the operation of finishing is complete.

60 We make no separate claim for the mechanism of the cutter-carrying head B³ in this application, as it forms the subject-matter of an application filed by us October 5, 1903, Serial No. 175,729, for improvements in a 65 mechanism for finishing the ends of barrels.

The slide o is moved longitudinally across the face of the revolving heads B³ B³ in the direction of the arrow shown in Fig. 4, as shown in the illustration, although the machine may be constructed in manner to cause said slide o 70 to move in either direction, as desired.

It is seen from an inspection of Fig. 4 that as the slide o moves to the right the chamfering-cutter f is brought in contact with the inside of the end of the barrel, thereby cutting a chamfer. At the same time the leveling-cutter e is drawn inward to cut the ends of the staves off to an equal length. The longitudinal movement of the slide o is communicated to the slides p p' through the medium 80 of an extension of the slide o, extending outward from it at each side, the ends of which carry the rolls p² p³, which slide in the angular grooves p⁴ and p⁵, thereby imparting an outward movement to each of the cutter-slides 85 p p', causing the crozing-knife h to contact with and cut a groove in the inside of the end of the barrel at the same time the howeling-cutter g smooths off the inside of the end of the barrel on each side of the crozing-groove. It will be understood that the reverse movement of the reciprocating shaft l draws the slide o back and through it the slides p and p' back out of contact with the inside or chime of the barrel after it is finished, leaving 95 said cutters e, f, g, and h in position where the head-block B may be moved outward from the end of the barrel in order that it may be released from the machine.

The cutters e, f, g, and h are adjustably secured to cutter-heads q q' q² q³, which cutter-heads are adjustably secured to the slides o, p, and p' by means of suitable adjusting-bolts having heads which fit and slide in the T-grooves r r r r r. Lugs u' u' u' u' are adjustably secured to the slides o, p, and p' and are provided with adjusting-screws u u and u² u², arranged to contact with the inner ends of the cutter-heads q, q', q², and q³. The cutters e, f, g, and h are mounted on the cutter-heads 110 q², q³, q', and q, respectively. When it is desired to adjust either of the cutters e, f, g, or h, the bolts fastening down the cutter-heads q², q³, q', and q, respectively, are loosened and the heads adjusted in or out, as desired, by turning the adjusting-screws u, u, u², and u² to the desired adjustment, when the securing-bolts are tightened. The adjustment just referred to is for the purpose of enabling the operator to finish the inside of the chime 115 of a barrel to the proper dimensions.

C represents a barrel in dotted lines, and C' represents gages or positioning-fingers which are mounted upon the arms C² C², which arms are in turn mounted upon the reciprocating 125 shaft C³, which is operated by the cam D, mounted upon the shaft b⁵. The cam D contacts with the roll D², attached to the end of a slideable lever D³, which in turn is pivoted to the rocker-arm D⁴, secured to the shaft C³, 130

The reciprocating movement imparted to the shaft C^3 by means of the cam D operates to eject the barrel or throw it out of the machine when finished. This mechanism, through the

5 medium of the fingers $C' C'$, mounted on the arms $C^2 C^2$, adjusts the barrel properly, so that when the head-stocks $B B$ move inward the end of the barrel will be presented to the circular opening in the clamping-rings $B^4 B^4$, which 10 hold the barrel while the operation of finishing its ends is being performed.

$E E$ are yielding fingers which are adapted to contact and move with the barrel when it is being forced into the retaining-rings $B^4 B^4$ 15 and to pull it out from said ring when the heads $B B$ recede from the ends of the barrel. Said fingers $E E$ are mounted upon reciprocating rods $E' E'$, which rods are moved inward by contact with the clamping-rings B^4

20 B^4 and are locked in position by means of the locking-bolt E^2 , so that when the heads $B B$ and the rings $B^4 B^4$ are moved outward after the barrel is finished the fingers $E E$ will be held inwardly and against the barrel and 25 hold it firmly from moving longitudinally in either direction and operate to pull it out from the clamping-rings $B^4 B^4$. When the clamping-rings $B^4 B^4$ and heads $B B$ have moved outward to their extreme position, the

30 reciprocating rods $E' E'$ are unlocked by the withdrawal of the locking-bolt E^2 through the means of the lever E^3 , the end of which is moved outward by contact with the cam-surface E^4 , mounted upon the cam b^4 . The said 35 rods $E' E'$ are moved away from each other by means of the spiral springs $E^5 E^5$, one end of which is attached to them, the other portion of the spring being secured upon the studs $E^6 E^6$, mounted on the bed A .

40 The heads $B^3 B^3$ are revolved through the medium of belts on the pulleys $B' B'$, running on pulleys on proper counter-shafts. The mechanism for sliding the heads $B B$ and the reciprocating shafts $l l$ is driven by means of 45 the pulley d^7 , having a belt running thereon from a pulley on a suitable counter-shaft. The shaft d^7 may be stopped or started by means of the clutch s , mounted upon the shaft d^5 and operated by the rod s^2 , attached 50 to the shaft s^4 , and the levers s^3 , mounted on the shaft s^4 , through the medium of the handle s^5 .

The movement of the reciprocating shafts $l l$ is again controlled by means of the clutch 55 t on the shaft b^5 , which enmeshes with the clutch member on the hub of the cam m , the clutch t being operated by the handle t' , mounted on the bracket t^2 .

The clutches s and t are intended to be used 60 in case of emergency and when it is necessary for any reason to stop the longitudinal movement of the head-stocks $B B$ or to prevent the cutters from coming into cutting contact with the barrel end. When in operation, the machine continues to make and repeat all the

movements required to clamp, finish the ends of a barrel, release it from the clamping-rings, and eject it without any manipulation of the operator.

The operation of our improved barrel-finishing machine is as follows: Assuming the heads $B B$ to be moved apart, as shown in Fig. 1, a barrel is placed upon the guides $C' C'$ and the clutch member s thrown into gear, when the heads $B B$ will move inward until the 70 ends of the barrel are firmly clamped in the rings $B^4 B^4$. The clutch t is then thrown in and the reciprocating shafts $l l$ are moved inward through the medium of the cam m , slide-block l' , the levers l^1 , which have rolls working in 80 the groove l^6 , the lever l^5 , the link l^4 , rocker-arm l^3 , rocker-shaft l^2 , and the lever l^1 . The movement of the parts just described causes the reciprocating shafts $l l$ to move inward, as before stated, thereby moving the slide o 85 and through it the cutters e and f , which operate to chamfer and level off the ends of a barrel at the same time the howeling-cutter g and the crozing-cutter h are moved outward and perform the operation of howeling and 90 crozing the end of the barrel, it being understood that the operation just described of finishing the end of a barrel takes place at both ends at the same time by substantially the same means. After the cutters e , f , g , and 95 h have performed their various operations of finishing the ends of the barrel the operating parts of the machine continue so that the cam m , through its various connections, will move the cutters out of contact with the barrel end, 100 and the cams $b^4 b^4$ then move the heads $B B$ outward out of contact with the barrel, the fingers $E E$ operating to pull the ends of the barrel out of the clamping-rings $B^4 B^4$. During the operation of pulling the ends of the 105 barrels out of the rings by means of the fingers $E E$ the cam b^4 will have revolved to a point where the contact-cam E^4 mounted thereon will have come in contact with the end of the lever E^3 , thereby releasing the finger-bars 110 $E' E'$, when same will be moved outward and out of contact with the ends of the barrels through the means of the springs $E^5 E^5$ ready for the insertion of another barrel. In the meanwhile the cam D will, through the medium of the roll D^2 which contacts therewith, move the lever D^3 upward and through the medium of the rocker-arm D^4 throw the arms $C^2 C^2$ upward and eject the finished barrel from 115 the machine. The arms C^2 are then returned to the position shown in Fig. 4 through the reverse of the operation just described.

It will be noted that the arms E and E' are automatic in their action, being moved inward by the inward movement of the heads $B^4 B^4$, 120 and serve to hold the barrel evenly between said heads, so that its ends will enter said heads an equal distance and also serve to pull the barrel out of the heads $B^4 B^4$ when they are moved outward and hold it equidistant 125 130

between them, so that the barrel can be thrown out by the ejectors without the danger of its catching on either of said heads.

Having described our mechanism and its operation, what we claim is—

1. In a machine for finishing the ends of barrels, a bed; platens slidably mounted on said bed; means operated by the main shaft for moving the said platens longitudinally in both directions; head-stocks adjustably mounted on said platens; clamping-rings secured to said head-stocks; cutter-carrying heads revolubly mounted in said head-stocks; cutters mounted on said cutter-carrying heads; and means operated through the medium of the main shaft for moving said cutters into cutting contact with the ends of a barrel. 65
2. In a machine for finishing the ends of a barrel, a bed; platens slidably mounted on said bed; head-stocks adjustably mounted on said platens; a main driving-shaft mounted in said bed; intermediate shafts in said bed and driven from said main driving-shaft; cams on one of said driving-shafts, said cams adapted to move the platens longitudinally; clamping-rings secured to said head-stocks; cutter-carrying heads revolubly mounted on said head-stocks; means for revolving said cutter-carrying heads; leveling-cutters, chamfering-cutters, crozing-cutters and howeling-cutters slidably and adjustably mounted on said cutter-carrying heads; cams for moving said cutters into cutting contact with the ends of a barrel, movable through the medium of levers mounted on the head-stocks; a slide-block mounted on the bed adapted to contact with the ends of said levers; a cam mounted on one of said intermediate shafts for operating the slide-block, as set forth. 70
3. In a machine for finishing the ends of barrels, comprising a bed; a slideable platen; head-stocks mounted thereon; clamping-rings in said head-stocks; cutters revolubly mounted on said head-stocks; adjustable gages for positioning the barrel in line with the clamping-rings; and adjustable fingers for holding the barrel central between the clamping-rings, and for withdrawing the barrel from both clamping-rings, substantially as described. 75
4. In a barrel-finishing machine, a bed, having platens slidably mounted thereon; head-stocks adjustably mounted on said platens; clamping-rings mounted on said head-stocks; adjustable gages mounted on said bed; positioning and withdrawing fingers mounted on said bed; and means for releasing said positioning-fingers and for ejecting the barrel when finished. 80
5. In a barrel-finishing machine, a bed; longitudinally-slidable platens mounted thereon; means for moving said platens longitudinally; head-stocks adjustably mounted in said platens; clamping means mounted on said head-stocks; means for positioning the barrel lat- 85
- erally and longitudinally so that it will enter said clamping-rings; means for withdrawing the barrel from said clamping-rings; and means for automatically releasing and ejecting said barrel from the machine when finished. 90
6. In a machine for finishing the ends of barrels, a bed; platens slidably mounted on said bed; head-stocks adjustably mounted on said platens; means for moving said platens longitudinally; clamping means mounted on said head-stocks; means for positioning a barrel both laterally and longitudinally, so that its ends will enter said clamping-rings an equal distance; and means for automatically releasing the positioning means when said barrel is finished. 95
7. In a machine for finishing the ends of a barrel, means for clamping the ends of a barrel; means for finishing the end of a barrel, comprising a revolving cutter-carrying head, and means for moving it longitudinally; guides on the face of said cutter-carrying head; cutter-carrying blocks slidably mounted in said guides; cutters adjustably mounted on said cutter-carrying blocks; a cam mounted in said cutter-carrying head for moving said cutter-blocks radially, said cam being so shaped and arranged as to cause the leveling-cutter to complete its cut before the chamfering-cutter, and to cause the crozing-cutter to complete its cut before the howeling-cutter; and means for operating said cam from the main driving-shaft by means of intermediate shafts, gearing, and a cam mounted thereon operating a slide-block as set forth. 100
8. In a machine for finishing the ends of a barrel, comprising a bed; clamping-rings and head-stocks longitudinally slidable thereon; cutter-carrying heads revolubly mounted in said head-stocks; cutters mounted on said revolving heads and adapted to move radially thereon, said cutters being moved into and out of cutting contact with the ends of a barrel by means of a driving-shaft and intermediate shafts having cams mounted thereon, operating-levers attached to cams in said cutter-carrying heads as set forth. 105
9. In an automatic machine for finishing the ends of barrels, adjustable to finish barrels of different lengths, comprising means for positioning, clamping, finishing both ends of a barrel, releasing and ejecting the same, all said means being operated by a driving-shaft revolubly mounted in the bed of said machine. 110
10. In a machine for automatically clamping and finishing the ends of barrels of different lengths, comprising a bed; platens slidably mounted on said bed; and head-stocks longitudinally adjustable on said platens; revoluble cutter-carrying heads mounted in said head-stocks; cutters slidably mounted on the inner faces of said cutter-carrying heads; means for moving said cutters radially through 115

the medium of levers mounted upon the headstocks, said means comprising an intermediate shaft mounted in bearings attached to the bed; a cam mounted on said intermediate shaft; a 5 slide-block slidably mounted in guides attached to the bed; a longitudinal groove in said slide-block adapted to receive and move the ends of said levers to cause the cutters to move into and out of cutting contact with the 10 ends of a barrel to finish the same; and a driv-

ing-shaft adapted to drive said intermediate shaft, as set forth.

In witness whereof we have hereunto set our hands, in the presence of two subscribing witnesses, this the 27th day of March, A. D. 1903. 15
